UNITED STATES PATENT OFFICE.

HARRY B. WREN, OF WASHINGTON, DISTRICT OF COLUMBIA, ASSIGNOR OF THIRTEEN-FORTIETHS TO JOHN I. CASSEY, OF FOREST GLEN, MARYLAND, AND WALTER R. HENSEY AND M. LEROY GOUGH, CONSTITUTING FIRM OF HENSEY & GOUGH, OF WASHINGTON, DISTRICT OF COLUMBIA.

MECHANISM FOR MAKING AND BREAKING ELECTRIC CIRCUITS.

SPECIFICATION forming part of Letters Patent No. 729,482, dated May 26, 1903.

Application filed May 27, 1902. Serial No. 109,195. (No model.)

To all whom it may concern:

Be it known that I, HARRY B. WREN, a citizen of the United States, residing at Washington, District of Columbia, have invented 5 certain new and useful Improvements in Mechanisms for Making and Breaking Electric Circuits, of which the following is a specification, reference being had therein to the accompanying drawings.

10 This invention has relation to mechanisms for making and breaking electric circuits; and it consists in the novel construction and arrangement of its parts, as hereinafter described.

15 The object of this invention is to provide a keyboard adapted to operate levers and switches, whereby electric circuits are completed to electrically-operated elements, such as signs, bells, machines, lights, &c. A mechanism is provided for cutting off the current and causing the various parts of the mechanism to assume their original or normal positions.

20 The novelty of this invention resides principally in the mechanism for completing the electric circuits, said mechanism adapted to be operated by a keyboard similar to that of a type-writing machine.

In the accompanying drawings, Figure 1 is 25 a top plan view of the apparatus. Fig. 2 is a transverse sectional view of the apparatus. Fig. 3 is a top plan view of a portion of the lever-revolving mechanism. Fig. 4 is a transverse sectional view of the lower portion of the apparatus. Fig. 5 is a perspective view of 35 one of the levers and a switch. Fig. 6 is a series of sectional and end views of the lever and switch, showing the various positions of these parts with relation to each other. Fig. 40 7 is a perspective view of one of the switches and a portion of the annulus upon which the outer end of the said switch operates. Fig. 8 is a diagrammatic view showing method of forming the letter "H" on a monogram.

45 The apparatus consists of stationary up- rights 11, mounted on a base 2. Arranged

within the uprights 11 is a tier of annuli 3, said annuli being also stationary and equal in number to the elements to be operated. Upon each annulus 3 rests the outer end of a 50 series of switches 4, the number of switches on each annulus being the same as the number of elements to be operated. The switches of the various annuli are arranged in perpendicular rows and pivoted at the points 5. The 55 inner ends of said switches are of a special construction, (hereinafter to be explained,) while the outer ends of said switches are adapted to pass under and come in contact with the under surface of the leaves 6. (See 60 Fig. 7.) The said leaves 6 being insulated by the material 7 from the annuli, one pole of the electric generator is connected to the annulus 3 at the point 8, while the opposite pole of the said generator is disconnected through 65 the elements operated to each of the leaves 6 at the point 9. The switch 4 being of metallic material, when the outer end of said switch 4 passes under the leaf 6 a circuit is completed from annulus 3 through said switch to 70 leaf 6. Adjacent to the outer end of each switch 4 is a stop 10; located on the annulus 3, which limits the movement of the switch in that direction.

A series of switch-operating levers 11 are 75 fulcrumed on the upright 12. The inner end of each lever 11 is provided with a ring 13, which surrounds the perpendicular rods 14, the upper end of each said rod being attached to a key-lever 15. Each of the perpendicular 80 rods 14 is provided with a series of lugs 16, which are adapted to pass under the rings 13 of a series of levers 11, and thus when the rod 14 is elevated, the lugs thereof engaging the rings of a series of levers 11, the said rings 85 are elevated and the opposite ends of the said levers 11 are depressed and caused to engage the ends of the switches 4 opposite the said levers, and thus as the said levers revolve (as will be hereinafter explained) the switches 4 90 are turned on their pivotal points and the outer ends of the same are carried under the

leaves 6 and the electric circuits to one of the elements to be operated are completed.

The mechanism for revolving the levers 11 consists of a perpendicular shaft 17, fixed at 5 its lower end to the base 2, said shaft being provided with a loose pulley 18, around which a belt may pass. The cog-wheel 19 is fixed to said pulley 18, and located below the said cog-wheel is a stationary disk having at its 10 edge the serrations 21, each serration having one edge extending substantially radially with the wheel 19 and a second edge extending at an angle to the radially-extending edge. The frame 22 is also fixed to the shaft 15 17 and the upright 12 is also fixed to said frame. The catch 23 is pivoted to the upright 12, said catch having an inwardly-extending rod 24, which normally abuts against the side of the lug 25, which in turn is attached to the 20 lever 26. The spring 27 is attached to said catch 23, said spring having a tendency to force the lower end of said catch toward the center of the apparatus. A dog 28 is located on said catch, and at intervals the said dog 25 is adapted to engage the cogs of the wheel 19. The lower end of the catch 23 is provided with a friction-roller 29, which is adapted to engage the serrated periphery of the disk 20. By referring to Fig. 2 it will be seen that 30 each rod 14 is provided with a lug which passes under the ring 13 of the lever 26. Thus at the operation of any key the ring of the lever 26 is elevated, which lifts the lug 25, and the spring 27 draws the lug 28 into engagement with the cogs of the wheel 19, as 35 shown in detail in Fig. 3. The wheel 19 revolving in the direction of the arrow, as shown in Fig. 3, the levers 11 are passed around to the next set of switches. As this is done the 40 roller 19, engaging the slanting edge of one of the serrations 1, carries the lug away from and out of engagement with the cogs of the wheel 9, and thus in turn draws the rod 24 back to the position as shown in Fig. 2, and the ring 13 of the lever 26 falls by gravity 45 and the lug 25 passes behind the end of the rod 24, and thus the parts are held in this position ready for the operation of another key.

50 The operation, as above described, may be repeated until the levers 11 have described a circle, and consequently electric circuits have been completed to all of the elements to be operated. The operator then turns the 55 crank 30, which is attached to the shaft carrying the gear-wheel 21, which meshes with the gear 32, which is located on the ring 33, said ring 33 having a series of upright bars 34, which pass by the sides of the switches 4, 60 and thus as the bars are moved toward the switches the outer edge of said switches are moved simultaneously from under the leaves 6 and the circuits to all the elements are broken and the parts are in their normal 65 positions.

Referring to Fig. 6, *a* shows the relative position of the end of the switch 4 and the lever 11 before the said lever is made to descend in the path of said switch. *b* shows the relative position of the switch and lever 70 ends when the lever is made to descend in the path of the switch and engage the same. *c* shows the relative positions of the switch and lever ends when the lever end passes over the switch without operating the same. 75

It will be understood that by operating a particular key the current may be sent to any predetermined series of elements, so as to produce by direct or indirect means the desired end of differentiating the optical appearance of said elements or predetermined series of elements, and thereby to produce graphically at will any desired letter, numeral, or character in luminous or colored design, and also to produce audible signals 80 and for operating electrically mechanisms of any character at a distance far or near.

Having described my invention, what I claim as new, and desire to secure by Letters Patent, is—

1. A device for making and breaking electric circuits consisting of a series of terminals, a series of switches for each series of terminals, said switches adapted to connect the terminals, a series of key-operated levers 95 adapted to operate simultaneously each series of switches successively.

2. A device for making and breaking electric circuits consisting of a series of terminals, a series of switches for each series of terminals said switches adapted to connect the terminals, a series of key-operated levers adapted to operate simultaneously the switches of one series and a means for moving said levers to permit them to operate the remaining 105 series of switches.

3. A device for making and breaking electric circuits consisting of a series of terminals, a series of switches for each series of terminals, said switches adapted to connect the 110 terminals, a revolving series of key-operated levers adapted to operate each series of switches successively.

4. A device for making and breaking electric circuits consisting of a series of terminals, 115 a series of switches for each series of terminals, said switches adapted to connect and disconnect the terminals, a series of key-operated levers adapted to operate each switch successively and cause them to engage the terminals and a means for simultaneously disengaging all of the switches from all of the 120 terminals.

5. A device for making and breaking electric circuits consisting of a series of terminals, 125 a series of switches for each series of terminals, said switches adapted to engage and disengage the terminals, a series of key-operated levers adapted to operate each series of switches successively, a mechanism for 130

changing the positions of the key-operated levers, said mechanism adapted to cause the levers to move from one series of switches to another, when the levers are operated and 5 permit the said levers to remain at rest when the key attachment of the lever is not operated.

In testimony whereof I affix my signature in the presence of two witnesses.

HARRY B. WREN.
